US00D763583S

(12) **United States Design Patent** (10) **Patent No.:** **US D763,583 S**
Miller et al. (45) **Date of Patent:** **** Aug. 16, 2016**

(54) **PAPER PRODUCT**

(71) Applicant: **Georgia-Pacific Consumer Products LP**, Atlanta, GA (US)

(72) Inventors: **Joseph H. Miller**, Neenah, WI (US); **Sarah A. Lemke**, Appleton, WI (US); **Brian J. Schuh**, Appleton, WI (US); **Steven R. Olson**, Menasha, WI (US); **John H. Dwiggins**, Neenah, WI (US); **Ryan A. Andersen**, Appleton, WI (US); **Morgan C. Perry**, Cincinnati, OH (US); **Juliette S. Portisch**, Columbus, OH (US); **Luke A. Gurtowski**, Neenah, WI (US)

(73) Assignee: **Georgia-Pacific Consumer Products LP**, Atlanta, GA (US)

(**) Term: **14 Years**

(21) Appl. No.: **29/516,680**

(22) Filed: **Feb. 5, 2015**

(51) LOC (10) Cl. **05-06**

(52) U.S. Cl.

USPC **D5/20; D5/39**

(58) **Field of Classification Search**

USPC D5/1, 6-8, 11-14, 16, 17, 19, 20, D5/23-26, 28, 30, 32, 35-39, 43, 46-48, D5/50, 51, 54, 56-66, 99; D6/304, D6/575-577, 582-589, 595, 596, 598, 600, D6/602, 609, 614, 619; D19/1, 5, 7; D25/102, 138, 139, 151

(57) **CLAIM**

The ornamental design for a paper product, as shown and described.

DESCRIPTION

The sole FIGURE is a top plan view of a paper product. The outer perimeter of broken lines defines the boundaries of the claim and forms no part thereof. The paper product is flat and planar. Thickness forms no part of the claimed design.

1 Claim, 1 Drawing Sheet
